US0D1053077S

(12) **United States Design Patent** (10) Patent No.: **US D1,053,077 S**
(45) Date of Patent: ** Dec. 3, 2024

(54) **MOTORCYCLE BATTERY BOX**

(71) Applicant: **Ruilifeng Industrial Technology (Shanghai) Co., Ltd**, Shanghai (CN)

(72) Inventor: **Xinhua Liu**, Jiangmen (CN)

(**) Term: **15 Years**

(21) Appl. No.: **35/520,017**

(22) Filed: **Dec. 22, 2023**

(80) **Hague Agreement Data**

Int. Filing Date: **Dec. 22, 2023**

Int. Reg. No.: **DM/234962**

Int. Reg. Date: **Dec. 22, 2023**

Int. Reg. Pub. Date: **Feb. 16, 2024**

(30) **Foreign Application Priority Data**

Oct. 10, 2023 (CN) 202330652211.3

(51) LOC (14) Cl. **12-11**

(52) U.S. Cl.

USPC **D12/114**

(58) **Field of Classification Search**

(57)

CLAIM

The ornamental design for a motorcycle battery box as shown and described.

DESCRIPTION

1.1 : Perspective

1.2 : Front

1.3 : Back

1.4 : Top

1.5 : Bottom

1.6 : Left

1.7 : Right

1 Claim, 7 Drawing Sheets
